DESIGN.

J. A. MOSHER.
ARC LAMP FRAME.

No. 26,649.

Patented Feb. 16, 1897.

UNITED STATES PATENT OFFICE.

JOHN A. MOSHER, OF CHICAGO, ILLINOIS, ASSIGNOR TO THE ADAMS & WESTLAKE COMPANY, OF ILLINOIS.

DESIGN FOR AN ARC-LAMP FRAME.

SPECIFICATION forming part of Design No. 26,649, dated February 16, 1897.

Application filed November 27, 1896. Serial No. 613,702. Term of patent 14 years.

To all whom it may concern:

Be it known that I, JOHN A. MOSHER, a citizen of the United States, residing at Chicago, in the county of Cook and State of Illinois, 5 have invented and produced a new and original Design for Electric-Arc-Lamp Frames; and I do declare the following to be a full, clear, and exact description of the same, reference being had to the accompanying drawings, forming a part thereof.

The design relates to the frame of electric-arc lamps, its object being to combine in the form of the frame symmetry and gracefulness with strength and efficiency. Its novelty re- 5 sides in the features hereinafter described.

In the accompanying drawings, illustrating the design, Figure 1 is a side elevation of the frame. Fig. 2 is a cross-section on the line 2 2 of Fig. 1.

The main portion of the frame is substantially **U**-shaped and comprises the approximately parallel arms A A, which have their lower ends inturned and united, as shown at a. A cross-bar D connects these two arms 5 approximately one-third of their length from their lower ends, and their upper ends are secured to a plate B.

A pair of parallel rods E E are located between the upper portions of the two arms A A 5 and extend between the plate B and the cross-bar D. A similar pair of parallel rods F F

depend from the connecting member a of the **U**-shaped frame, and the lower ends of these rods are united by a plate or bar f. The rods F F may be of any desired length. As shown, 35 they are somewhat shorter than the rods E E.

The cross-bar D and the member a of the **U**-shaped frame are centrally vertically apertured, and the connecting plate or bar f may be similarly apertured. As shown, these 40 several apertures are not of uniform diameter, that of the upper one being the greatest and of the lower one the least. This feature, however, is not an essential one, as the apertures may be uniform in size. Neither do I 45 desire to be limited to the precise shape in cross-section of any of the several members of the frame, the essential elements of the design being the **U** shape of the main portion of the frame, the cross-bar uniting the up- 50 right members of this portion, and the two pairs of parallel rods E E and F F.

I claim—

The design for an arc-lamp frame, substantially as shown and described. 55

In testimony whereof I affix my signature in presence of two witnesses.

JOHN A. MOSHER.

Witnesses:

LOUIS K. GILLSON,
SAKE D. THOMPSON.
